UNITED STATES PATENT OFFICE

163,706

COMBINED TRAY AND CONDIMENT SHAKERS

Ernest Nukanen, New York, N. Y.

Application June 23, 1950, Serial No. 10,719

Term of patent 7 years

(Cl. D44—22)

To all whom it may concern:

Be it known that I, Ernest Nukanen, a citizen of the United States of America, and a resident of New York, in the county and State of New York, have invented a new, original, and ornamental Design for Combined Tray and Condiment Shakers, of which the following is a specification, reference being had to the accompanying drawing, forming part thereof, in which—

Fig. 1 is a top plan view of a combined tray and condiment shakers embodying my new design.

Fig. 2 is a cross-sectional view taken on the line 2—2 of Fig. 1.

Fig. 3 is a composite view in cross-section of the salt and pepper shakers and the tray, respectively.

I claim:

The ornamental design for a combined tray and condiment shakers, as shown.

ERNEST NUKANEN.
